CHARLES V. LINDBLOOM, OF CRANFORD, NEW JERSEY, ASSIGNOR, BY MESNE ASSIGNMENTS, TO HI-HEAT GAS CO. INC., OF NEW YORK, N. Y., A CORPORATION OF NEW YORK

VALVE FOR GAS BURNERS

Application filed May 23, 1928. Serial No. 280,078.

There is on the market a fuel in the form of a liquid which is generally sold in containers and the fuel is adapted to be used for household and other gas stoves, the fuel being converted from the liquid to the vapor phase just before it reaches the point of combustion. The fuel is made by liquefying natural gas. The object of the present invention is to provide a valve which will serve to vaporize the fuel and while it is particularly adapted for use with the kind of fuel described above, nevertheless the invention is not limited to this particular purpose. In burning fuels, particularly the kind described, which is converted from a liquid to a vapor, it is customary to employ a needle valve to control the feed of the fuel to the burner and to cause the fuel to be atomized as it is discharged from the needle valve. One of the difficulties of former devices has been that in first starting the operation of the burner, as when the gas is turned on and is ignited at the burner, there is a sudden rush of gas which causes the flames from the burner to rise considerably above the normal condition. There is also a tendency for the burner to make considerable noise when first started, and in addition the action at the time of starting is irregular and otherwise objectionable. The present device makes it possible to start the burner without the sudden flashing up of the flames, and to start it practically noiselessly. Where the present device is used, as soon as the needle valve is opened a match may be held over the burner and the gas will ignite and burn smoothly, quietly and with the same character of flame as when the burner has been in operation for some time. In addition, the burner at all times operates more smoothly, more regularly, and is under more perfect control where the present invention is employed than with the ordinary needle valve heretofore used. I have found that by passing the fuel successively through two orifices which have the effect of breaking up the fuel, and by providing a small expansion chamber for the fuel in which it may expand after passing through the first restricted orifice and before it passes through the second restricted orifice, the

improved results above named may be accomplished. Further advantages and details of my invention will be set forth in the following description.

In the drawing forming part of this application. 55

Figure 1 is a plan view of a burner with my improved valve applied thereto.

Figure 2 is an elevation, partly in section, and showing the details of my improved 60 valve,

Figure 3 is a sectional view taken on the line 3—3 of Figure 2,

Figure 4 is a sectional view on an enlarged scale of the two members in which the restricted orifices are formed, and 65

Figure 5 is an end view of one of these members.

In the drawing I have shown an ordinary burner which may comprise one of the burners commonly used in a gas range, and it consists of the several hollow radially arranged members 1 having apertures 2 in the top wall, from which the gas is discharged, and above it the gas burns in the form of flames. As far as my present invention is concerned, this burner may take any form, and I have illustrated one type of burner merely by way of illustrating one application of my invention. Preferably, the burner is provided with an extension 3 in communication with two of the radial members 1 and this extension is provided with a number of apertures 4 to provide flames which will serve to preheat the fuel while it is passing through the atomizing valve for the purpose of rapidly vaporizing the fuel. These features are per se all in common use at the present time. 70 75 80 85

The curved neck 5 serves to feed the fuel to the burner 1, and my improved valve may be conveniently applied to the outer end of this curved neck (as shown in Figure 1). There is a coupling member 6 provided with a longitudinal bore 7 extending therethrough, and there is a lateral bore 8 by means of which the fuel is conveyed to the longitudinal bore by means of the tube 9 threaded into the coupling 6 and which tube leads from any suitable source of supply, such as one of the small tanks or cartridges in which the fuel is sup- 90 95 100

plied to the consumer. The valve spindle 10 projects at 11 beyond the coupling 6 and its outer end is provided with an operating handle 12 by means of which the valve spindle is 5 adapted to be operated. Where the valve stem projects through the end of the coupling there is preferably a nut 13 for holding a packing or stuffing in close fit around the portion 11 of the valve spindle to prevent the escape of fuel. There is a reduced portion on 10 the spindle provided with a thread 14 which co-operates with the thread 15 in the reduced portion of the bore 7 of the coupling 6, so that by turning the valve spindle these threads co- 15 operate to cause the spindle to move either to the right or left in Figure 2. The fuel which enters the lateral bore 8 in the coupling 6 passes into a chamber 16 which is a portion of the bore of the coupling and the fuel is adapt- 20 ed to be entirely shut off at this point by means of a valve 17 which is merely a frustoconical shoulder on the valve stem 10 which is adapted to seat against the valve seat 18 composed of a shoulder in the coupling member 6. I 25 have also shown a tubular member 19 threaded into one end of the coupling 6 as shown at 20 which tube forms a continuation of the coupling member; that is to say, the bore 21 of this tubular extension and the bore 7 of 30 the coupling member form a continuous passage for the fuel. The valve spindle 10 has a reduced portion 22 which extends along the bore of the tubular extension 19 but it does not fill this bore, so that an annular space 23 35 between this spindle and the member 19 permits the fuel to pass through the tubular member. I have shown a coiled spring 24 surrounding the reduced portion 22 of the spindle near one end of the latter, which serves as 40 a bearing for this end of the spindle, which bearing however, permits the fuel to pass the coils of the spring.

The portions of the valve forming the main features of my invention may be constructed 45 in various ways, but I will here describe the form which I prefer to use, both for simplicity and for accessibility. There is a cap 25 provided with an internal threaded bore 26 and this is adapted to cooperate with an external thread 27 on the outer, free end of the tubular member 19. The cap 25 may be provided with a polygonal flange 28 to receive a wrench for the purpose of screwing the cap onto the tubular member 19. This cap has 55 an end wall 29 in which is formed a vaporizing chamber 30, preferably of conical shape, and open at one end into the bore 26 of the cap. The opposite, smaller end of this vaporizing chamber merges with a small orifice 31 which forms an opening in the head 29 of the cap. There is a plug or filler 32 shown enlarged in Figure 4, which has a laterally extending flange 33 on its periphery. This plug or filler is adapted to slide in the bore 65 26 and to seat against the shoulder 34 ad-

jacent the larger end of the vaporizing chamber 30. When seated in this position the end of the tubular member 19 seats against one side of the flange 33 and surrounds the tubular portion 35 of the filler member, so that no fuel can pass, except through the restricted orifice hereinafter described. The filler or plug 32 is provided with a restricted orifice 36 and preferably there is a conical chamber 37 communicating with this orifice.

The end of the valve spindle is provided 70 with a needle 38 which extends through the restricted orifice 36 and the point of this needle co-operates with the restricted orifice 31 in the head 29 of the cap. The orifice 36 is slightly larger than the diameter of the needle 38, so that there is an annular space 80 between the needle and the filler member 32 through which the fuel may pass into the expansion chamber 30. In the adjustment of 85 the needle there is no alteration in this annular space between the needle and the filling member 32 as I have found that the regulation of the fuel may be controlled entirely by the co-operation of the point of the needle with the orifice 31. The latter orifice is, preferably, slightly smaller than the orifice 36.

Operation

When it is desired to start the burner, a lighted match may be held over the burner openings 2, and the valve handle 12 is turned slightly, so that the valve stem moves to the left in Figure 2. This unseats the valve 17 100 from the seat 18 and allows the fuel to pass from the supply pipe 9, through the port 8, into the chamber 16 of the coupling 6. From there the fuel passes through the annular space between the spindle 10 and the tubular member 19, passing through the convolutions of the bearing member 24 and the fuel then passes into the conical opening 37 in the filler member. It then passes through the annular space between the needle 38 and the wall of 105 the orifice 36. Where the device is used for the character of fuel referred to above, the fuel will remain in the liquid state until it passes through the orifice 36 at which time it will be broken up or atomized into a vapor 110 and enter the expansion chamber 30. The fuel may expand in this latter chamber and accumulate, and from this chamber it passes through the orifice 31 which further breaks up and atomizes the fuel, so that by the time 115 it passes into the neck 5 it is completely vaporized. The fuel passes through the neck 5 into the burner and as it emerges from the apertures 4 it is ignited and combustion takes place in the form of a number of jets, 120 depending upon the number of apertures in the burner. Several jets are projected from the apertures 4 and are caused to strike the tubular member 19 for the purpose of pre-heating the fuel while it is passing through 125 130

this tubular member, in order to expand it and assist in the vaporizing action, or in the conversion of the fuel from the liquid to the vapor state.

5 By passing the fuel first through the orifice 36 and then into an expansion chamber 30 it allows it to expand and accumulate and by then passing the fuel through the second orifice 31 I have found that more perfect 10 regulation in flow of the fuel may be obtained and that all of the difficulties heretofore occurring more especially during the starting of the burner, and to some extent during operation thereof, are eliminated. 15 As the fuel passes through the first orifice 36 it is atomized and it is expanded in the chamber 30 so that when it passes through the second orifice 31 it is further atomized. By the time, therefore, that it discharges 20 from the orifice 31 the fuel is fully vaporized even at the beginning of the operation, and before the heat projected against the tube 19 has raised the temperature of the fuel within this tube. This arrangement of double orifices with an expansion chamber between them also prevents any back action or tendency to backfire previous to the heating of the fuel in the tube 19. The regulation of the flow of fuel is accomplished by 25 30 turning the handle 12 in order to vary the position of the point of the needle 38 in relation to the orifice 31. While the needle moves in relation to the member 32 it does not necessarily change the size of the first orifice 36. This is not necessary as the regulation at the second orifice 31 is sufficient to control the feeding of the vapors to the burner. It is not necessary, although desirable, that the first orifice as represented by the 35 40 space between the needle 38 and the wall of the orifice 36 should be annular and it is preferable also that the fuel enter the cone shaped pocket 37 just previous to passing through the first orifice.

45 Having described my invention, what I claim is:

1. A valve for atomizing fuel, including a tube for the passage of the fuel, a cap having a restricted outlet orifice and an expansion chamber adjacent thereto, said cap having a threaded bore adapted to screw onto said tube, a filling piece insertible into said bore of said cap and having a restricted orifice in communication with said expansion chamber, and a needle passing through said last mentioned orifice and co-operating with said first mentioned orifice to regulate the flow of fluid.

2. A valve for atomizing fuel, including a tube through which the fuel passes, a cap for said tube having an end wall provided with an outlet orifice and having an expansion chamber adjacent said orifice, said cap having a threaded bore adapted to be threaded onto said tube, a filling member insertible

into said cap and having a lateral flange and a tubular projection, said tubular extension being adapted to fit the bore of said tube, said lateral flange being adapted to be clamped between the end of said tube and the end wall of said cap, said filling member having an orifice communicating with said expansion chamber, and a needle for regulating the flow of fluid through said orifices.

Signed at the city, county, and State of New York, the 6th day of April, 1928.

CHARLES V. LINDBLOOM.
